UNITED STATES PATENT OFFICE.

WILLIS N. HARTSHORN, OF RACINE, WISCONSIN.

GRINDING MILL.

Application filed December 26, 1919. Serial No. 347,371.

To all whom it may concern:

Be it known that I, WILLIS N. HARTSHORN, a citizen of the United States, and resident of Racine, in the county of Racine and State 5 of Wisconsin, have invented new and useful Improvements in Grinding Mills, of which the following is a description, reference being had to the accompanying drawings, which are a part of this specification.

10 The present invention relates to certain new and useful improvements in grinding mills and more particularly to mills of that type used for reducing mineral or vegetable substances through several reductions 15 or grindings as may be necessary to secure the desired degree of fineness in the finished product.

My invention has for one of its objects to provide a mill of this class which will require a minimum amount of floor space in 20 that the several grinding units are imposed one above the other with their axes substantially in vertical alignment.

Another object of my invention is to provide a grinding mill including several units 25 arranged one above the other which are so constructed that any one or more of the units may be readily removed from the mill without disturbing the other units or any portion 30 of the driving mechanism of the mill.

The grinding mills now in general use are so constructed that when it is desired to resurface the faces of the stones of the various units it is necessary that the same be done 35 at the mill proper which is very undesirable in that particles of stone, dirt and the like contaminate the products in adjacent machines. Hence, with the above and other objections in mind my invention has for another 40 of its objects to provide a grinding mill so constructed that the grinding units thereof may be readily removed and taken bodily as a unit to a properly equipped room for dressing or refinishing the grinding surfaces of the stone in the most efficient manner.

A still further object of this invention is to provide a mill of the class described including a plurality of readily removable 50 grinding units which are so constructed that the units may be readily independently adjusted. A still further object of my invention is to provide a novel form of feed control which may be readily adjusted to vary 55 the amount of material supplied to the grind-

ing units or which may be operated to completely shut off the supply of material without the necessity of shutting down the mill so that the mill may be run sufficiently long after the supply of material therein has been 60 cut off to insure the discharge of the material which may be therein.

With the above and other objects in view which will appear as the description proceeds my invention resides in the novel construction, combination and arrangement of parts substantially as hereinafter described and more particularly defined by the appended claims, it being understood that such changes in the precise embodiment of the 70 herein disclosed invention may be made as come within the scope of the claims.

In the accompanying drawings I have illustrated one complete example of the physical embodiment of my invention constructed according to the best mode I have so far devised for the practical application 75 of the principles thereof, and in which:

Figure 1 is a side view of a complete grinding mill embodying my invention, 80 parts being broken away and in section to more clearly illustrate the various details of construction.

Figure 2 is an elevational view looking at the rear of the mill.

Figure 3 is a side plan view of a lower portion of my machine illustrating one of the units as being removed therefrom and indicating the equipment I employ to remove the same from the machine.

Figure 4 is a fragmentary sectional view taken through the grinding unit adjusting member.

Figure 5 is a fragmentary sectional view taken on the plan indicated on the line 5—5 95 of Figure 1 through the said control mechanism.

Referring now more particularly to the accompanying drawings my invention may be said to broadly consist of a main machine 100 frame having a plurality of independent grinding units removably mounted therein, driving mechanism for operating the grinding units and so arranged as to permit the removal of any of the grinding units without 105 effecting the operation of the remaining units, means for readily independently adjusting the grinding units, readily variable means for feeding material to the first grinding unit and means for conveying the ma- 110

2
terial discharged from one grinding unit to the next unit.

The machine frame consists of a base section 10, vertical side standards 11, a top transverse section 12 connecting the upper ends of standards 11, and rear transverse brace members 13 connecting the standards 11 as best shown in Figure 2. This arrangement provides a frame structure which is firmly secured against vibration and is so constructed as to permit the ready access to the various machine parts.

Secured to the inner faces of the standards 11 in spaced relation are bracket members 14 forming supports for the grinding units, and as the several grinding units are substantially alike the description of one will suffice for all. The grinding unit comprises a main casing 15 provided with a pair of oppositely laterally projecting supports or bracket members 16 adapted to be engaged with the adjacent pair of aligned brackets 14 of the standards 11 and secured thereto by bolts 17.

25 The casing 15 has a stone 18 secured therein by cement or other material 19, and has its upper end laterally directed as at 20 and then upwardly and outwardly directed to provide a trough 21 surrounding the upper portion of the stone 18. As best shown in Figure 1 the casing 15 is formed with a central bore 22 in which is journalled a spindle 23 having one end projected below the casing 15 and engaged with a thrust bearing 24 and its upper end supporting a revolvably mounted stone 25 for co-operating with the stationary stone 18. The stone 25 is cemented or otherwise secured in a casing or housing 26 and is centrally bored and has a retaining spider member 27 secured therein and provided with a key slot 28 for receiving a driving key 29 secured to the upper end of the spindle 23. The members 27 of the uppermost grinding unit has a collar or sleeve 30 entering therein for adjustable connection with the material feed control mechanism to be later described, and the members 27 of the other units are provided with a funnel-shaped opening 31 into which the discharge ends of the material conveying members extend, as will be later described.

The stone 18 is rigid with the fixed casing 15 and the stone 25 is rigid with its casing 26 which is rotated with the spindle 23 by means of the key 29 between said spindle and spider 27 which is fixed to the casing 26. The means for rotating the spindle 23 and consequently the stone 25 consists of a large spur gear 32 splined to the portion of the spindle 23 projecting below the casing 15 and disposed above the thrust bearing 25, which spur gear is meshed with a smaller spur gear 33 fixed to a vertical driving shaft 34 journalled in bearings 35 centrally formed in the braces 13 and base 10. The

shaft 34 has a bevel gear 36 splined thereon near its lower end and meshed with a bevel gear 37 splined to a shaft 38 journalled in the upper ends of supports 39 secured to the base 10 and one of the standards 11 and adapted to be drivingly connected with a drive pulley 40 by suitable clutch mechanism 41. The pulley 40 is connected with any desired source of power (not shown) in any desired manner and the bevel gears 36 and 37 are normally enclosed by a protecting housing or guard 42.

The spur gear 32 is enclosed by a housing 43 firmly secured to the housing 15 and forming a substantial part thereof, the spur gear 33 meshing with gear 32 through an opening 44 in the casing 43, and said gear 33 being enclosed by a guard 45 secured to the casing 43 as at 46.

From this description it will be readily seen that the shaft 34 is rotated through means of its connection with the drive pulley 40 and the stone 25 is revolved by means of its connection with the shaft 40 through the gears 33 and 32, spindle 23 and key connections 29.

This arrangement of driving mechanism permits the ready removal of any of the units without effecting the drive of the remaining units as the connection between the spur gears 32 and 33 of the remaining units is not disturbed in any manner. When it is desired to remove any one of the units it is simply necessary to disconnect the securing means 46 between the guard 45 and the casing 43 so that when the unit is removed the gears 32 and 33 may be readily disengaged.

As best shown in Figure 1 the large spur gear 32 has its face of less width than the face of the small gear 33 to permit the vertical movement of the spur gear 32 of the grinding units with the revolvable stone 25 when moved to its various positions of adjustment by means now about to be described.

The thrust bearing 24 has its upper portion exteriorly threaded as at 47 and in threaded engagement with a cap or housing 48 centrally secured in the bottom of the casing 43 and has its lower portion provided with gear teeth 49 in mesh with a worm gear 50 secured to the end of a shaft 51 journalled in bearings 52 and having a hand wheel 53 secured to its outer end.

To adjust the distance between the grinding surfaces or faces of the stones 25 and 18, the thrust bearing 24 is adjusted by means of the hand wheel 53 which adjusts the same with respect to the cap 48 to raise or lower the stone 25. A sleeve member 54 is secured to the spindle 23 to protect the bearing 22 in bore 22. The faces of the gears 32 being of different widths permits the ready movement of the large spur gear with the spindle 23 to various adjusted positions as will be

apparent without disturbing its driving connection with the small spur gear 33.

The substance to be ground is fed to the uppermost or first grinding unit of the machine from a hopper 55 secured to the top frame section 12 and having its discharged end disposed in alignment with the collar or sleeve 30 slidably and rotatably mounted within the member 27, by means of a sleeve 56 carried by the feed control mechanism and telescoping within the sleeve 30 so that the stone 25 may be readily adjusted without disconnecting the sleeve 30 and the member 27. Disposed between the hopper 55 and the sleeve 56 is a cylindrical member 57 having one end solid and its other end provided with spaced longitudinally extending recesses 58, and said member is adapted to be rotated so that when the recesses 58 are aligned with the discharge end of the hopper 55 and the sleeve 56 the material will be discharged from the hopper by said recesses.

The member 57 is freely journalled upon a shaft 59 journalled in bearings 60 formed on support brackets carried by the frame section 12 and is movable along the shaft 59 to align either its recessed portion or its solid portion with the discharge end of the hopper 55 or else to partly align the recessed portion and the solid portion of said member with the discharge end of the hopper to control the feed of material from the hopper. The means for moving the member 57 along the shaft 59 consists of a screw shaft 61 having its inner end rotatably secured to the frame and having its outer portion in threaded engagement with spaced ears 62 of a bracket member 63 having a yoke 64 engaged in an annular groove 65 of the member 57 so that the movement of the bracket 63 toward or away from the frame will effect a corresponding movement of the member 57.

The bracket 63 is moved by means of a hand crank 66 secured to the outer end of the screw shaft 61 and adapted to be rotated in either direction corresponding to the desired movement of the member 57 as will be obvious. The member 57 is operated in connection with the shaft 59 by means of a clutch member 67 slidably splined to the shaft and adapted to engage a clutch portion 68 formed on the member 57, and said clutch is moved to and from engagement with the section 68 by means of a lever 69 pivotally carried by the bracket 63. By reason of the lever 69 being carried by the bracket 63 the operation of the same is not affected by the various adjustments of the member 57.

By this construction it is possible to control the feed of material from the hopper and to disconnect the member 57 from the drive shaft 59 irrespective of its position on said shaft without effecting the drive

of the grinding units so that the same may continue to operate until the material between the stones of the various units has been expelled therefrom. The shaft 59 is rotated by means of a drive pulley 70 having a belt connection 71 with the vertical drive shaft 34 as best shown in Figures 1 and 2.

The material after it has entered the first grinding unit and reduced between the stones thereof is discharged into the trough 21 and then outwardly from the trough 21 through a discharge spout 72 into the receiving end of a screw conveyor 73 readily removably disposed within brackets 74 secured to the under side of the casing 43 and having its discharge end 75 positioned within the mouth 31 of the spider member of the next grinding unit. After the material has been further reduced by the next grinding unit it again passes into the trough 21 thereof through spout 72 and is conveyed to the next grinding unit by means of a similar conveyor 73 and then it is discharged from the last grinding unit through a spout 76 to be discharged to suitable containers or conveyors (not shown).

The conveyors 73 are readily removably secured in the brackets 74 as it is necessary to remove the same before the unit carrying the same is removed from the machine frame. The conveyors are driven by suitable belt connections 77 connecting the drive pulleys 78 of the conveyors with drive pulleys 79 fixed to the end of shaft 59 remote from its drive pulley 70.

As is common in the art, the stationary stone 18 may be heated by means of heating coils 80 connected by means of inlet and discharge pipes 81 and 82 respectively with a supply pipe 83 and a discharge pipe 84.

In Figure 3 I have illustrated the improved structure I employ for handling the several units of the mill and transporting the same from the mill to a room where the same may be worked upon in the most efficient manner. This structure consists of a pair of horizontal parallel frames or tracks 85 having their inner ends secured to the standards 11 at a point adjacent the brackets 14 and having their outer ends supported upon vertical standards 86. When it is desired to move a grinding unit, the tracks 85 are secured in position and the bolts 17 securing the unit to the brackets 14 are removed and suitable means provided for drawing the unit upon the tracks 85.

The means for driving the unit upon the track 85 consists of a toothed rack 87 adapted to have its inner end secured as at 88 to the bracket 16 of the unit and having its outer end in mesh with a toothed gear 89 fixed to a shaft 90 journalled in a bearing 91 fixed on the outer end of the track 85. An operating handle 92 is fixed to the shaft 90

so that the shaft 90 and its gear 89 may be rotated to move the rack 87 away from the mill frame and with it the grinding unit.

As depicted in Figure 3, the intermediate unit is shown as being mounted upon the track 85 and the revoluble stone as suspended by means of a lifting cable 93 connected with the stone by a yoke member 94.

The supports 86 are of various heights so that the track 85 may be secured to the standards 11 in line with the bracket 14 of the unit which it is desired to remove.

What I claim as my invention is:

1. A grinding mill, comprising a plurality of superimposed grinding units, each unit including a pair of cooperating grinding members, a drive spindle for one grinding member of each unit, a drive gear mounted on each spindle, a drive shaft common to all units, a drive pinion secured on said shaft adjacent each drive gear and meshed therewith, and means engageable with the drive spindles for adjusting the grinding members of the units, the drive pinions being of greater width than the drive gears whereby adjustment of the spindles will not disturb the connections between the units and the drive shaft.

2. A grinding mill, comprising a supporting frame, a plurality of grinding units mounted in the frame in superimposed relation with their axes in alinement, a drive shaft journaled in the frame and common to said units, independent gear connections between said shaft and each unit, means for conveying materials passed through one unit to the next unit, and means whereby any of said units may be removed horizontally from the frame without disturbing the drive and operation of the remaining units.

3. In a grinding mill, means for supplying materials to be ground to the mill, comprising a supply hopper having a depending discharge spout, a cylindrical member rotatably mounted at the discharge end of said hopper spout and having one end solid and one end recessed, means for rotating said member, and means for sliding said member lengthwise to aline either end of said member with the discharging spout of said hopper, said solid end, when in alinement with the discharge spout, shutting off the supply of materials from said hopper, and said recessed end, when in alinement with said discharge spout, permitting the materials from

said hopper to be fed from the grinding mill.

4. In a grinding mill, means for supplying materials to be ground to said mill, comprising a supply hopper, a revolubly mounted cylindrical member disposed at the discharge end of said hopper having a solid portion and a recessed portion, drive means for rotating said member, means for aligning either part of said member with the discharge end of said hopper, and clutch means carried by said member in its various positions for connecting and disconnecting the same with the drive means.

5. A grinding mill comprising a frame, a plurality of grinding units removably secured in the frame in superimposed axially alined relation and each consisting of a casing, a stationary stone mounted in the casing, a spindle journaled in the casing, a revoluble stone co-operating with the stationary stone and drivingly connected with the spindle, and means for rotating the spindle.

6. A grinding mill comprising a mill frame, a grinding unit secured in said frame and including a stationary stone, a revoluble stone co-acting with the stationary stone, and means for adjusting the spaced relation between said stones, and means for operatively driving said grinding units, said means including a rotatably and vertically adjustably mounted spindle having its upper end connected with the revoluble stone, an adjustable thrust bearing engaging the lower end of said spindle, a spur gear splined to the spindle adjacent its lower end, and a spur gear of greater width than the other spur gear and in mesh therewith to drive the same and rotate said revoluble stone.

7. In a grinding mill, a main frame including spaced standards, series of supports carried by the standards, a plurality of grinding units mounted between the standards in vertical alinement and removably supported one by each series of supports, a drive shaft journaled in the frame, and drive connections between the units and the drive shaft, said units being capable of ready independent removal without disturbing the drive of the other units.

In testimony whereof, I affix my signature.

WILLIS N. HARTSHORN.
